BALANCING MACHINE FRAME

Fred R. Bokorney, Westchester, Ill.

Application April 3, 1953, Serial No. 24,353

Term of patent 14 years

(Cl. D52—1)

To all whom it may concern:

Be it known that I, Fred R. Bokorney, residing in the city of Westchester, county of Cook, and State of Illinois, have invented a new, original, and ornamental Design for a Balancing Machine Frame, of which the following is a specification, reference being had to the accompanying drawing, forming a part hereof.

Figure 1 is a perspective view of a balancing machine frame, illustrating my new design.

Figure 2 is a plan view of the machine illustrated in Figure 1.

The characteristic features of the design reside in the solid line portion.

I claim:

The ornamental design for a balancing machine frame, substantially as shown and described.
